Primary Examiner — Martie K Holtje(74) *Attorney, Agent, or Firm* — Holtz, Holtz, Goodman & Chick PC(57) **CLAIM**

The ornamental design for a wrist watch, as shown and described.

DESCRIPTION

FIG. 1 is a reduced scale front, right side, bottom perspective view of a wrist watch showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a reference front elevational view thereof; and,
FIG. 9 is a reference right front perspective view thereof,
drawn to a reduced scale with respect to FIG. 1.The broken lines in FIG. 8 illustrate a state in which the wrist watch is electrified which form no part of the claimed design.
The straps depicted by broken lines in FIG. 9 represent environment that forms no part of the claimed design.**1 Claim, 8 Drawing Sheets****FIG. 1**
